Inventor:

Ward T. Simpson,

by Spear, Middlelin, and Abbott, Attys.

UNITED STATES PATENT OFFICE.

WARD T. SIMPSON, OF GRAND RAPIDS, MICHIGAN, ASSIGNOR, BY MESNE ASSIGNMENTS,
TO ALBERT G. DICKINSON, OF GRAND RAPIDS, MICHIGAN.

CARBURETOR.

Application filed October 21, 1920, Serial No. 418,422. Renewed February 2, 1927.

One object of the present invention is to provide a carburetor having a vacuum fuel chamber for drawing in its own fuel and a fuel nozzle arrangement adapting the organization for use where a horizontal type of mixing chamber is desired.

Other objects of the invention will appear from the following description.

In the drawings:

10 Figure 1 is a sectional view of the carburetor taken longitudinally of the mixing chamber and nozzle.

Fig. 2 is a view partly in section and at right angles to Fig. 1 and on line 2—2 of 15 Fig. 1.

Fig. 3 is a detail showing a section along the air and fuel tubes.

Fig. 4 shows the system on a car.

20 In these drawings 1 indicates a fuel chamber provided with a float 2 and a valve 3 controlled thereby, said valve being balanced by the depression within the fuel chamber.

From this fuel chamber a vacuum passage 4 extends, said passage at its end being defined by a wall surrounding a horizontal tube 4^a forming the mixing chamber. This vacuum passage connects with the engine manifold by a narrow annular passage 5 surrounding the discharge end of the mixing 25 tube. The fuel nozzle comprises an air nozzle 6 having an outwardly flared inlet opening 7 and an outwardly flared outlet opening 8, these walls defining the central bore sloping to the contracted intermediate area 9, at which the end of the fuel pipe 10 is located.

This fuel pipe is inserted laterally through the nozzle and it has its end bevelled off so that its high point 11 is nearest to the inlet, 40 from which point its edge slopes downwardly at an inclination to the axis of the nozzle and towards the outlet end. The end of the pipe at all points is above the inner wall of the nozzle. This fuel pipe extends 45 through a bracket 12 which extends across but is spaced apart from the intake opening of the mixing chamber tube, and affords a seat for an annular throttle valve B which surrounds the exterior of the tube 4^a and is 50 movable in the direction of its axis to and from its seat. The angular end of the fuel pipe provides for aspiration of the fuel by the inflowing air.

55 Provision is made for introducing air into the fuel pipe to control the amount of fuel

flowing therethrough to meet the various conditions of operation and for this purpose an air pipe extends into the nipple 13 carried by the bracket 12 and communicates with the interior of the fuel pipe. This air 60 metering pipe is arranged at an inclination upwardly and outwardly from the fuel pipe as shown in Fig. 3 and there will be no tendency for air bubbles to lodge or pocket in its inlet to the fuel pipe and thus interfere with the proper flow of fuel to the nozzle. This air tube is controlled by a valve 15, which fits a long tapered seat at 16.

Air is introduced into the fuel pipe at all times except in starting, at which time it is 70 shut off. This may be done by any suitable connection leading to the seat of the driver.

Such connections are old and well known and are not shown herein. Instead of arranging the fuel pipe at right angles to the 75 axis of the nozzle, I may arrange it on an inclination thereto, but in any event the end of the fuel pipe will enter the bore of the nozzle and the plane of its end face will be at an inclination to the axis with its highest point or tip nearest to the inlet, so that the end face will slope downwardly towards the inner end of the nozzle.

I provide a drain hole at 14 leading from the vacuum passage to the fuel chamber, so 85 that if any liquid precipitates on the walls it will be led back to the fuel supply.

It will be noticed that there is considerable restriction at the point *a* between the tip of the fuel pipe and the wall of the 90 nozzle. This gives high velocity to the air at this point and from this point the space gradually enlarges. Depression at the discharge opening of the fuel pipe is created for forcibly drawing in the fuel. Restriction is also obtained at *b* between the lip of 95 the air nozzle and the wall of the mixing tube by reason of the outward flare of the discharge end of the nozzle.

At idling position a high velocity is obtained at the end of the fuel pipe and practically no velocity at the outside restriction *b* because there is little air passing at this time, the throttle valve being nearly closed.

The depression in the fuel chamber and 105 outlet of the nozzle is practically the same at the idling period, but it is the greatest at the outlet of the nozzle, thereafter depending on the flow of air at the restriction *b*.

Any ordinary set of connections may be employed for operating the throttle valve.

I claim:—

1. In a carburetor, the combination of a fuel bowl having an upward extension with a tube extending horizontally through said extension, supported by the wall thereof and forming between itself and a part of said extension a surrounding chamber 4 and with a restricted annular passage 5, a ring shaped throttle valve slidably mounted on the extension of said horizontal tube, a bracket extending from the lower part of the fuel bowl upwardly and having a seat portion opposite the said horizontal tube and serving as a seat for the ring shaped throttle valve, a nozzle extending from said seat portion into the horizontal tube, said nozzle having its central opening continued through the seat portion, and an oil supply conduit extending through the bracket and discharging into the nozzle, substantially as described.

2. In a carburetor, the combination of a fuel bowl having an upward extension providing a passage communicating the bowl above its fuel level with the engine intake, a tube extending horizontally into said passage, and supported in said extension, and having an end portion projecting from said extension, a ring shaped throttle valve slidably mounted on the projecting end of said horizontal tube, a bracket extending from the lower part of the fuel bowl upwardly and having a seat portion opposite the said horizontal tube and serving as a seat for the ring shaped throttle valve, a nozzle extending from said seat portion into the horizontal tube, said nozzle having its central opening continued through the seat portion, and an oil supply conduit extending through the bracket and discharging into the nozzle, substantially as described.

In testimony whereof, I affix my signature.

WARD T. SIMPSON.
